(57) **CLAIM**

The ornamental design for a combined drink pod holder and basket, as shown and described.

DESCRIPTION

FIG. 1 is a front top perspective view of a combined drink pod holder and basket showing our new design;

FIG. 2 is an enlarged view of the grid member shown in FIG. 1 which is mounted within the circular base area enclosed by the basket outline to form the bottom of the basket of the combined drink pod holder and basket;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view showing the grid member removed for ease of illustration thereof; and,

FIG. 8 is a bottom plan view showing the grid member removed for ease of illustration thereof.

The broken lines showing portions of a basket and grid member of the combined drink pod holder and basket is for the purpose of illustrating environment, and forms no part the claimed design.
